Levi Bronson INVENTOR, BY

Burke, Fraser & Dagood
Atty's.

UNITED STATES PATENT OFFICE.

LEVI BRONSON, OF BUFFALO, NEW YORK.

IMPROVEMENT IN THRASHING-MACHINES.

Specification forming part of Letters Patent No. 122,354, dated January 2, 1872.

SPECIFICATION.

I, LEVI BRONSON, of Buffalo, in the county of Erie and State of New York, have invented certain new and useful Improvements in "Concaves" of Thrashing-Machines, of which the following is a specification:

Nature of the Invention.

My invention consists in horizontally adjusting the concaves of thrashing-machines nearer to or further from the thrashing-cylinder, and in the means whereby this is accomplished, as hereinafter described.

General Description.

In the drawing, Figure 1 is a cross-section of the cylinder and concaves. Fig. 2 is a plan, with the cylinder and concaves removed, showing the adjusting devices.

A is the frame; B B', two curved concave supports or hangers, having horizontal slots *a a'* in the upper end instead of vertical ones, and connected by a rod, *b*, at the lower end, as shown. This rod projects through the hangers B B' into horizontal slots *c c'* in the side pieces of the frame A, and which run parallel with slots *a a'* in the upper ends of the hangers. C is a drawing-rod, bent at an angle, and secured at either end to the rod *b*, just inside the hangers, and provided at its point with a screw-hole, *d*. *e* is the moving screw, which passes through this hole *d*, and also through cross-piece D of the frame A, and is held therein by a collar, &c., as shown in Fig. 1. A wrench or crank, *f*, or its equivalent, operates the screw from the outside. E is the cylinder, and F the front grate or front portion of the feed-board, which moves with the concaves. The slots *a a'* have pins *g*, upon which they slide. It will readily be seen that by merely turning the wrench *f* the concave will be moved horizontally forward or backward. The main object in moving them in this way instead of up and down is to widen the space at or near the feed-board, while the space at the bottom and exit part is kept the same. This facilitates feeding, as some kinds of grain need the teeth of the concave and thrashing-cylinder closer together than others.

It is common to raise the concaves of thrash-

ing-machines up nearer to the cylinder, or lower them by various devices, which, with some kinds of grain, makes the feeding process more difficult; while by my invention of the horizontal movement the space between the concaves and thrashing-cylinder is not varied at the lower edge, as before stated, but the feeding-entrance is widened to facilitate feeding. In the old method of adjusting up and down, the front grate attached to the concaves is raised up with them, making a steeper incline, and the wooden feed-board which rests on the edge of the front grate is flattened in position, the break making a short angle to feed over, which, with some kinds of grain, is quite detrimental. By my horizontal movement of the concaves the line of the front grate and feed-board remain always at the same angle which is an important consideration, as it is always desirable to keep the original angle, which is set for all kinds of grain. The adjusting can be done by the party feeding the machine, either with his foot or hand without getting off, the crank or handle being just beneath him. In the other methods the adjustment is from the side, and has to be attended to by another party.

Having thus described my invention, what I claim as new, and desire to secure by Letters Patent, is—

1. The combination of the concave supports B B', horizontal slots *a a'* and *c c'*, rod *b*, and studs *g*, all arranged and operating in connection with the drawing or adjusting-rod C and thrashing-cylinder E, as herein shown, whereby a horizontal adjustment of the concaves to or from the thrashing-cylinder is secured.

2. The drawing-rod C, screw-hole *d*, screw *e*, and handle *f*, in combination with the rod *b*, grate F, curved concaves B B', horizontal slots *a a'* and *c c'*, studs *g g*, and thrashing-cylinder E, all constructed, arranged, and operating substantially as and for the purpose set forth.

In witness whereof I have hereunto signed my name in the presence of two subscribing witnesses.

LEVI BRONSON.

Witnesses:

J. R. DRAKE,
C. N. WOODWARD.
